UNITED STATES PATENT OFFICE.

JAY W. BRIGGS, OF RACINE, WISCONSIN.

BOOK-MARK.

No. 921,356.

Specification of Letters Patent.

Patented May 11, 1909.

Application filed January 13, 1908. Serial No. 410,472.

To all whom it may concern:

Be it known that I, JAY W. BRIGGS, a citizen of the United States, residing at Racine, county of Racine, and State of Wisconsin, have invented new and useful Improvements in Book-Marks, of which the following is a specification.

My invention relates to improvements in book marks.

10 The object of my invention is among other things to provide a convenient, inexpensive and efficient means of producing and connecting together a plurality of index marks by which a number of different pages of a book may be indicated, the books readily opened at the indicated points while the particular line or paragraph of such page may also be indicated while such index marks may be readily removed to another book or changed from one place to another in the same book.

My invention is further explained by reference to the accompanying drawings in which,

25 Figure 1 represents a vertical section of a book provided with my marking device, the retaining mechanism of which is shown in vertical section. Fig. 2 represents an end view of a book provided with my marking device, part in section. Fig. 3 represents a modified form of one of the marking members removed from the book, and Figs. 4 and 5 represent horizontal sections drawn on lines X—X, and Y—Y of Fig. 1.

35 Like parts are identified by the same reference characters throughout the several views.

1 represents the side covers, 2 the leaves, 3 the back of the cover, and 4 the back of the 40 binding of a book.

My apparatus comprises a plurality of marking members 5 provided at their respective ends with apertures 6, two overlapping adjustable members 7 and 8 which are slidably connected together by the clamping members 9 and 10 in such a manner that such members 7 and 8 may be extended and contracted to conform to the length of different books, 11 and 12 are loops by which the marking members are connected with the members 7 and 8. The clamping member 7 is provided with an inwardly and downwardly extending arm 13 and the clamping member 8 is provided with an upwardly and inwardly extending arm 14, and said arms 13 and 14 are respectively

inserted in the spaces between the back of the cover 3 and the back of the binding 4.

It will be understood that the clamping members 9 are formed integrally with the upper end of the member 8 and that it partially incloses the opposing member 7, also that the members 10 are formed integrally with the member 7 and partially incloses the member 8 as indicated in Figs. 4 and 5. That the clamping members 9 engage loosely around the clamping member 7, while the clamping members 10 engage loosely around the clamping member 8 in such a manner as to slidably connect said members 7 and 8 together as stated.

The loops 11 and 12 are formed of a single piece of sheet metal bent in a semi-circular form shown and their overlapping ends 15 and 16 are connected with the respective members 7 and 8 at the ends of the book and they serve to hold the several marking members 5 in place. The marking members 5 are respectively provided with angular slits 17 through which the loops 11 and 12 are free to enter the apertures 6 of said marking members as such members are secured in place in a book. The marking members 5 are preferably formed of a celluloid, a tough quality of paper or similar material which is sufficiently flexible to permit the respective sides of the slits 17 to be sprung apart when inserting the loops. For the purpose of shielding the ends of marking members and the retaining loops from contact as the book is handled, I preferably provide the slideable members 7 and 8 with the end plates 18, 18, which extend inwardly from the back of the cover to shield such parts. The marking members 5 serve to indicate the pages of the book, while I have provided the members 20 which are adapted to slide upwardly and downwardly upon the members 5 to indicate the special lines or paragraphs on such pages.

The slideable members 20 are preferably provided with index characters arranged numerically in the manner shown which aid the user of the book to determine the desired point of opening the same. As a convenient means for fastening the member 20 to the members 5, I have provided the same with two longitudinal slits 21 and 22, when the ends of the members 5 are inserted through the slit 21 above the central tongues 23 and back through the slit 22, when the member 20 will be retained at any desired point of adjustment by the resilient action of such

coöperating parts. While I have shown the marking members 5 within the book, provided at its respective ends with apertures 6, in the modified form shown in Fig. 3 the marking member 5' is provided with but a single aperture 6', and slit 17' while the lower horizontal arm together with the loop retaining aperture is dispensed with.

Having thus described my invention what 10 I claim as new and desire to secure by Letters Patent, is,

1. In a book marking device of the described class, the combination of two overlapping members slidably connected together, means for temporarily connecting said members with the back of a book, a plurality of marking members radially connected with said slidable members and adapted to be folded with and between the 20 leaves of a book.

2. In a book marking device of the described class, the combination of two overlapping members slidably connected together, means for temporarily connecting said members with the back of the book, a loop attached to one of said sliding members, a plurality of longitudinally arranged marking members, and means for slidably connecting said marking members with said 30 loop.

3. In a book marking device of the described class, the combination of two overlapping members slidably connected together, means for temporarily connecting said members with the back of a book, a plurality of marking members arranged longitudinally of the book, means for temporarily connecting said marking members with said 35 slid able members, and a transversely arranged marking member slidably supported upon said longitudinal marking member.

4. In a book marking device of the described class, the combination of two overlapping members slidably connected together, means for temporarily connecting said members with the back of a book, a plurality of marking members arranged longitudinally of the book, means for temporarily 40

connecting said marking members with said over-lapping members, a transversely arranged member slidably supported upon each of said marking members, the protruding ends of said slideable marking members being respectively provided with index characters. 50

5. In a book marking device of the described class, the combination of two overlapping members slidably connected together, a retaining hook formed integrally with each of said sliding members adapted to engage the back of the cover of a book, 60 circular loops connected with the ends of said slideable members, transversely arranged end plates connected with the respective ends of said members adapted to shield said loops from contact, a plurality of longitudinally arranged marking members provided with apertures for the reception of said loops and with transversely arranged slits through which said loops may enter and be removed from said apertures and a transversely arranged marking member slidably supported upon each of said longitudinal marking members. 65

6. In a book marking device of the described class, the combination of two overlapping members slidably connected together, means for temporarily connecting said members with the back of a book, a loop connected with the outer end of one of said slideable members, protecting end plates 70 formed integrally with the respective ends of such slideable members, longitudinally arranged marking members provided at one end with an aperture for the reception of said loop and with a slit through which said 75 loop may enter and be removed from said aperture and a transversely arranged marking member slidably supported upon said longitudinal member, all substantially as and for the purpose specified. 80

In testimony whereof I affix my signature in the presence of two witnesses.

JAY W. BRIGGS.
